UNITED STATES PATENT OFFICE

WILLIAM E. FOALE, OF WILKINSBURG, PENNSYLVANIA

ROLL FOR FLATTENING METAL SHEETS

Application filed September 5, 1928. Serial No. 204,127.

This invention relates to a roll for use in flattening stacked metal sheets after removal from an annealing furnace.

Such sheets, due to various conditions, such as their temperature, rolling in a hot mill, shearing, and stacking, are not of uniform thickness and are also distorted. In most instances, the sheets are thinnest along the longitudinal edge portions and are transversely cambered. Accordingly, a roll having a continuous surface parallel to the axis thereof cannot be moved evenly or reciprocated over the sheets, the tendency of the roll being to move from one side of the longitudinal median line of the sheet to the other side, with the roll in no instance being in contact with the sheets from end to end of the roller, that is, throughout its length.

It is the primary object of the present invention to provide a jointed or two-part roll which will automatically adapt itself to such camber so as to engage the sheets throughout the length of the roll, and also automatically vary or adapt itself to changes in the shape of the sheets as they are gradually relieved of camber or distortion through reciprocatory action of the roll thereover.

Another object is to provide a novel construction in which the roll is made in relatively movable interchanging sections flexibly connected by elongated bolts.

Additional objects and advantages will, in part, be pointed out and otherwise will become apparent from a consideration of the description following taken in connection with accompanying drawings illustrating an operative embodiment.

In said drawings:

Fig. 1 is a front elevation of the improved roll;

Fig. 2 is a central transverse sectional view, partly in elevation, taken on line II—II of Fig. 1;

Fig. 3 is a fragmentary longitudinal sectional view taken centrally through the roll;

Fig. 4 is a diagrammatic view, showing the roll applied to the curved surface of a sheet; and

Fig. 5 is a perspective view of the roll

Referring specifically to the drawings, the roll is made of two or more similar cylindrical metallic sections 10, through the center of each of which an exceedingly strong bolt or shaft 11 is loosely passed, such shafts at their inner ends having eyelets 12 in loose pivotal engagement with each other, and disposed in cutaway portions A formed in adjacent ends of said sections. The outer ends of said shafts or rods 11 project through the hubs 13 of sections 10. Beyond the hubs 13, nuts 14 may be threaded to the bolts, with washers 15 mounted on the shafts between the nuts and hubs, and with cotter-keys 16 passed through the shafts outwardly of the nuts to guard against loosening and loss of the latter.

The inner or facing ends of the roll sections 10 are spaced slightly apart to provide clearance for flexure or articulation of the roll. Projecting beyond said inner faces from each section 10 are studs 17. Said studs may be screw-threaded as at 18, to the respective sections 10, with those of one section arranged alternately with respect to the other section. Said sections have recesses 19 enlarged with respect to and receiving the free ends of the studs 17, so as to permit the flexure or articulation previously referred to.

The roll is adapted to be reciprocated or moved back and forth over a pack of metallic sheets 20 as taken from an annealing furnace, as previously mentioned. This movement may be accomplished in any desired way, but is preferably effected through the operation of a crane, adapted for connection to a strong bail 21, which in turn is fastened flexibly at 22 to rings 23 loose on the hubs 13.

A roll of the present character is exceedingly heavy and will usually weigh from five hundred pounds to two or three tons.

Presuming operation, the metallic sheets 20 in a pack or stack are to be rolled immediately after they are removed from an annealing furnace and while they are still

hot. Such sheets will almost invariably be transversely distorted or cambered, as suggested in the drawing. The arrangement of the rolls with their longitudinal axes transverse with respect to the sheets, due to the loose and flexible connection between them at the eyelets 12 and studs 17, will automatically adapt themselves to the shape of such sheets, and substantially throughout 10 their length engage the sheets.

The roll is then moved back and forth or reciprocated in order to flatten the sheets, during which action, the roll is guided, due to the camber and the fact that the roll sections will have their axes in slightly downwardly diverging relation to accord with the camber. The position of the axes of such roll sections automatically changes or varies as the camber is gradually straightened out or removed and the sheets become flat. Thus, the roll will not move from side to side as it is pulled back and forth over the sheets and, accordingly, can roll or flatten them more expeditiously and effectively than heretofore.

Another advantage of the present construction is that, in case of disablement, a new section 10 can be substituted without substituting a complete new roll. Further, in existing structures, they almost invariably break midway of their ends, where my sections 10 are flexibly connected. Danger of such breakage is thus overcome. In addition, such broken sections of an existing roll may be machined and made into a roll according to the present invention.

Various changes may be resorted to, provided they fall within the spirit and scope of the appended claims.

40 I claim:

1. A roll for flattening metal sheets consisting of sections in very slightly spaced relation and relatively movable in a substantially vertical direction, whereby they may automatically adapt themselves to the surface to be rolled, said sections having interlocking means adjacent the inner ends thereof.

2. A roll consisting of cylindrical sections arranged end to end in slightly spaced relation, shafts axially of the sections having interlocking means for flexibly connecting together adjacent meeting ends of the sections, whereby the sections are relatively movable in a substantially vertical direction so that they may automatically adapt themselves to the surface to be rolled, said adjacent ends having cooperating inter-engaging means.

60 3. A roll consisting of sections in slightly spaced relation and relatively movable in a substantially vertical direction, whereby they may automatically adapt themselves to the surface to be rolled, and means effecting 65 loose inter-engagement of the sections at

their facing ends, said means including shafts disposed axially of the sections and formed with cooperating engaging means, said sections at their adjacent ends formed to receive the cooperating engaging means.

70 4. A roll consisting of cylindrical sections arranged end to end in slightly spaced relation, shafts disposed axially of the sections having inter-engaged eyelets adjacent the facing ends of the sections, each of said ends having lugs extending beyond the same, said ends having recesses receiving said lugs and enlarged with respect to the same.

75 5. A roll consisting of cylindrical sections arranged end to end in slightly spaced relation, shafts disposed axially of the sections having interlocking means adjacent the facing ends of the sections, one of said ends having a projecting member thereon, and the other end a recess into which the 80 projecting member is entered.

85 6. A roll for flattening metal sheets, including a plurality of roll sections disposed in slightly spaced relations, said roll sections having inter-engaging means at adjacent 90 ends, and an axially disposed member extending loosely through each of the rolls.

95 7. A roll for flattening metal sheets, including a plurality of roll sections disposed in slightly spaced relations, said roll sections having inter-engaging means at adjacent ends, an axially disposed member extending loosely through each of the rolls, said member threaded at an outer end and a cooperating adjusting means on the 100 threaded portion.

8. A roll for flattening metal sheets, including a plurality of cylindrical roll sections arranged end to end in slightly spaced relation, a projecting member on one end of a section, and a recess in the adjacent end of another section to effect a loose connection therebetween.

In testimony whereof I affix my signature.

WILLIAM E. FOALE.
